UNITED STATES PATENT OFFICE.

ROBERT M. GILSON, OF PITTSBURGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed April 17, 1928. Serial No. 270,596.

My invention relates to railway traffic controlling apparatus of the type wherein train-carried governing mechanism is controlled by energy received from the trackway. More particularly my invention relates to what is known as coded train control systems. The present invention relates specifically to the trackway portion of such apparatus.

10 My invention is an improvement on the apparatus shown in United States Letters Patent No. 1,632,162, granted to C. R. Beall on June 14, 1927.

I will describe one form of apparatus embodying my invention, and will then point out the novel features thereof in claims.

The accompanying drawing is a diagrammatic view showing one form of apparatus embodying my invention.

20 Referring to the drawing, the reference characters 1 and 1^a designate the track rails of a railway along which traffic normally moves in the direction indicated by the arrow. These rails are divided by insulated 25 joints 2 into a plurality of track sections, of which only one section A—B is shown in the drawing.

Located at the entrance end of the section A—B is a centrifugal track relay R^A comprising two windings 4 and 5, the former of which is constantly connected with the track rails 1 and 1^a, and the latter of which is supplied with alternating current by means which will be explained hereinafter. This track relay also comprises a rotor 6, a centrifugal device 14 operated by the rotor 6, and two contacts 7 and 20 controlled by the centrifugal device 14.

40 The track relay R^A controls a coder relay F, which in turn controls a coder D, both of which are located adjacent the exit end of section A—B. The coder D may be of any suitable type, such, for example, as that shown in application for Letters Patent of 45 the United States filed by P. N. Bossart on Feb. 7, 1927, Serial No. 166,407. This coder comprises an operating winding 15, and two contacts 16 and 17 which are periodically closed while the coder is in operation, the 50 frequency of operation of contact 16 being different from that of contact 17.

Also located adjacent the exit end of the section A—B are two sources of current differing in frequency. As here shown,

these sources are a transformer C⁶⁰ and a 55 transformer C¹⁰⁰, the primaries of which are connected with alternating current generators, not shown in the drawing. The frequencies of the currents delivered by these transformers may, for example, be 60 cycles 60 per second and 100 cycles per second, respectively, although I do not wish to be limited to these particular frequencies.

When the coder relay F is energized, 60 cycle current is constantly supplied to the 65 track rails A—B by a transformer T, the secondary 18 of which is connected across the rails adjacent the exit end of the section through a limiting impedance 3. The primary circuit for transformer T is from the 70 left-hand terminal of the secondary of transformer C⁶⁰, through the front point of contact 19 of the coder relay F, and the primary 12 of transformer T to the right-hand terminal of the secondary of transformer C⁶⁰. 75 At the same time 60 cycle current is constantly supplied to the primary of a transformer E, the secondary of which is connected with winding 5 of track relay R^A. It will be seen, therefore, that under normal 80 conditions, that is, when the track section A—B is unoccupied, 60 cycle current is supplied to both windings 4 and 5 of relay R^A, and so this relay is effectively energized to hold its front contacts closed and its back 85 contacts open.

When the coder relay F is de-energized, the 60 cycle source is disconnected from transformers T and E, and 100 cycle current is supplied to the coder D through back 90 contact 18 of coder relay F, so that the coder D is set into operation. One hundred cycle current is then supplied to transformers T and E through the back contact 18 of coder relay F, contact 16 or 17 of coder D, 95 front point or back point of contact 23 of track relay R^B for the section next in advance of section A—B, and the back point of contact 19 of coder relay F. It follows that under this condition 100 cycle current, 100 periodically interrupted at one rate or another, is supplied to the rails of section A—B and also to winding 5 of track relay R^A, the rate of interruption of this current depending on whether track relay R^B 105 is energized or de-energized.

Heretofore in systems of this character it has been customary to control the coder re-

lay F through a back contact of track relay R^A , so that this coder relay is normally de-energized, but is energized when the back contact of the track relay becomes closed due to a train entering the section. On account of the time required for the closing of the back contact of a centrifugal relay after it has been shunted by a train, this means for controlling the coder relay is unsatisfactory, because it introduces an undesirable delay in the application of the coded current to the track rails after a train enters the section. In accordance with my invention, therefore, I control the coder relay F by a front point of contact 7 of the track relay R^A , so that this coder relay is normally energized and becomes de-energized as soon as the front contact of the track relay opens. It follows that the delay referred to above in the application of the coded current in the track rails is eliminated. As shown in the drawing, the main circuit for coder relay F is from terminal X of a suitable source of current, through the front point of contact 7 of relay R^A , and the winding of coder relay F to terminal Y of the same source of current.

With only the apparatus thus far referred to, the restoration of the track circuit to its normal condition after a train leaves section A—B would be less satisfactory than when the coder relay is normally de-energized and is controlled by a back contact of the track relay. I have accordingly provided means for de-energizing the coder relay F as soon as the back contacts of the track relay R^A open when the latter relay becomes energized due to a train passing out of the section. As here shown, I accomplish this by the provision of the slow-releasing relay G, having a circuit which is closed when the back point of contact 7 of track relay R^A becomes closed. Coder relay F is provided with an auxiliary circuit which passes from terminal X, through front contact 21 of relay G, resistance 22 and the winding of coder relay F to terminal Y. This auxiliary circuit is provided with a shunt around the winding of relay F, which shunt passes from resistance 22, through back contact 20 of track relay R^A to terminal Y.

The operation of the apparatus for controlling the coder relay F, is as follows: When a train enters section A—B, track relay R^A becomes de-energized, and as soon as the front point of contact 7 of this relay opens, the coder relay F becomes de-energized to apply the coded train governing current to the rails of the section. When the back point of contact 7 of a track relay R^A closes, relay G becomes energized, but relay F is not affected because it is shunted by back contact 20 of relay R^A which contact is then closed. When the train passes out of section A—B, relay R^A again becomes

energized, and as soon as back contact 20 opens, the shunt around relay F in the auxiliary circuit for this relay becomes open, so that relay F becomes energized by virtue of the circuit through contact 21, of relay G and resistance 22. The slow-releasing characteristic of relay G is such that the front contact 21 of this relay remains closed until after the front point of contact 7 of track relay R^A closes. It follows that when the train leaves the section, the coder relay F immediately becomes energized and continues to be energized as long as track relay R^A is energized. There is, therefore, no delay in the application of the coded train governing current to the rails when a train enters the section, and there is no delay in the restoration of the track circuit to its normal condition after a train leaves the section.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a section of railway track, a centrifugal track relay having a controlling winding connected with the rails of said section, a coder relay, a circuit for said coder relay including a front contact of said centrifugal relay whereby said coder relay is normally energized, a slow-releasing relay having a circuit including a back contact of said centrifugal relay whereby said slow-releasing relay is normally de-energized, an auxiliary circuit for said coder relay including a front contact of said slow-releasing relay, a shunt for said auxiliary circuit around the coder relay and including a back contact of said centrifugal relay, and means including a coder controlled by said coder relay for supplying the rails of said section with track circuit current when the coder relay is energized and with coded train governing current when the coder relay is de-energized.

2. In combination, a section of railway track, a centrifugal track relay having a controlling winding connected with the rails of said section, a coder relay, means controlled by said centrifugal relay for de-energizing said coder relay as soon as the front contact of the centrifugal relay opens and for again energizing the coder relay as soon as a back contact of the centrifugal relay opens, and means including a coder controlled by said coder relay for supplying the rails of said section with track circuit current when the coder relay is energized and with coded train governing current when the coder relay is de-energized.

3. In combination, a section of railway track, a centrifugal track relay having a controlling winding connected with the rails of said section, a coder relay, means controlled by said track relay for normally energizing said coder relay but for de-energizing the coder relay as soon as the front contact of the track relay opens, means also controlled by said track relay for again energizing said coder relay as soon as the back

contact of said track relay opens, and means including a coder controlled by said coder relay for supplying the rails of said section with track circuit current when the coder relay is energized and with coded train 15 governing current when the coder relay is de-energized.

In testimony whereof I affix my signature.

ROBERT M. GILSON.
